United States Patent Office.

WILLIAM N. MARTIN, OF PROVIDENCE, RHODE ISLAND.

Letters Patent No. 91,650, dated June 22, 1869; antedated June 10, 1869.

IMPROVEMENT IN SELF-CLEARING WATCH-KEYS.

The Schedule referred to in these Letters Patent and making part of the same.

To all whom it may concern:

Be it known that I, WILLIAM N. MARTIN, of Providence, in the county of Providence, and State of Rhode Island, have invented a new and useful Improvement in Watch-Keys; and I do hereby declare that the following is a full and exact description thereof, reference being had to the accompanying drawings, which constitute a part of this specification—

Figure 1 being a perspective view, representing the usual size of my improved watch-key;

Figure 2, an enlarged perspective view of the same; and

Figures 3 and 4 are enlarged longitudinal sections of said watch-key.

The same letters indicate corresponding parts in each of the drawings.

The square opening in the stem of my improved watch-key extends longitudinally through the same, and terminates in a cylindrical chamber, in the body of the key.

A core, *b c c d*, whose shape and location within the key are shown in figs. 3 and 4, is operated in the manner and for the purpose hereinafter set forth.

The enlargement, *c e*, of the key-core *b c c d*, fits accurately within the chamber in the body of the key, and the spring *f*, which encloses the short core-shank, *d*, and works between the core-enlargement *c e* and the closing-head *g*, of the hollow body of the key, serves the purpose of retaining the said core in the position shown in fig. 3, at all times when not used for winding a watch, and, consequently, when carried within the pocket of the owner, it will be impossible for any lint or dirt to accumulate within the winding-aperture in its stem, to be thence carried into the interior of a watch.

The pin *e*, which projects from the enlargement *c e* of the key-core, works in a longitudinal slit, *i*, in one side of the hollow body of the key, and the lateral recesses, or notches *k k*, at the upper end of said slit, enable the key-core to be caught and retained in the position shown in fig. 4, during the operation of winding a watch, the said operation being as follows:

When the key is pressed on to the winding-arbor of a watch, the key-core will, by said pressure, be forced inward until arrested by its pin *e* being brought to the end of the slit *i*, in the barrel of the key, and then the act of turning the key to wind the watch will carry the said core-pin *e* into one of the notches *k*, at the head of the slit *i*, and retain the key-core in its withdrawn position during the said winding-operation; and when that is accomplished, a slight reverse movement of said key will detach the core-pin *e* from its lodgment in either of its retaining-notches, when the spring *f* will instantly project the key-core to the protecting position shown in fig. 3.

Having thus fully described my improved watch-key, What I claim therein as my invention, and desire to secure by Letters Patent, is—

The dirt-excluding key-core *b c c d*, when operated in conjunction with the spring *f*, the core-pin *e*, and the notched or T-headed slit *i k*, substantially in the manner herein set forth.

The foregoing specification of my new and useful improvement in watch-keys signed and witnessed, this day of , 1868.

WILLIAM N. MARTIN.
